FIG. 1

FIG. 2

FIG. 3

FIG. 4

FIG. 5

FIG. 6

FIGURE 1 is a perspective view of the top, rear and one side of a flashlight embodying my design, both sides of the flashlight being identical;

FIGURE 2 is an enlarged plan view showing the top of the flashlight, including the switch;

FIGURE 3 is a frontal view of the flashlight;

FIGURE 4 is a side elevational view of the flashlight;

FIGURE 5 is a plan view showing the bottom of the flashlight; and

FIGURE 6 is an elevational view showing the rear of the flashlight.

The characteristic feature of my design resides in the simulated wood paneling on the bottom of the flashlight in combination with the configuration of the flashlight handle and head.

I claim:

The ornamental design for a flashlight, as shown and described.
